PIPE HANGER

Pasquale P. Cappola, 21 Emerald St., Quincy, Mass.
Filed Feb. 16, 1962, Ser. No. 173,731
5 Claims. (Cl. 248—74)

This invention relates to new and useful improvements in pipe hangers for use particularly although not necessarily, on ships and has for its primary object to provide, in a manner as hereinafter set forth, a pipe hanger which is adapted to be expeditiously installed beneath an insulated deck with a minimum of damage to the insulation.

Another very important object of the present invention is to provide, in a hanger of the aforementioned character comprising a saddle for receiving the pipe, novel means for quickly, firmly but removably securing the pipe in said saddle.

Still another important object of the invention is to provide an improved pipe hanger of the character set forth which is readily vertically adjustable relative to the deck or other overhead supporting structure.

Another object of the invention is to provide an improved hanger of the character described which is adapted to accommodate various sizes of pipe within a given range.

Other objects of the invention are to provide an improved pipe hanger which is comparatively simple in construction, strong, durable, compact, of light weight and which may be manufactured and installed at low cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of a pipe hanger constructed in accordance with the present invention, showing the device installed;

FIGURE 2 is a view in vertical section through the rear portion of the device, showing same installed;

FIGURE 3 is a sectional view on an enlarged scale through the connected end portions of the pipe securing strap or band, taken substantially on the line 3—3 of FIGURE 1;

FIGURE 4 is a vertical sectional view on an enlarged scale, taken substantially on the line 4—4 of FIGURE 2;

FIGURE 5 is a perspective view of the hanger per se without the suspension stud or rod;

FIGURE 6 is a view in side elevation of another embodiment of the hanger, showing same installed;

FIGURE 7 is a bottom plan view of the embodiment of FIGURE 6;

FIGURE 8 is a view in transverse section, taken substantially on the line 8—8 of FIGURE 6; and

FIGURE 9 is a perspective view of the clamp which is used on both embodiments of the hanger.

Referring now to the drawing in detail, it will be seen that the embodiment of the present invention which has been illustrated in FIGURES 1 to 5, inclusive, of said drawing comprises a threaded suspension rod, shank or stud 9 of suitable metal. The suspension stud 9 may also be of any desired length and diameter. The stud 9 extends upwardly through an opening 10 provided therefore in the insulation 11 beneath the steel ship deck 12 and has its upper end portion riveted or otherwise anchored in said deck, as indicated at 13. In the installation shown, the steel deck 12 is apertured as indicated at 14 to accommodate the stud 9.

Removably and adjustably mounted on the lower end portion of the suspension stud 9 is a generally U-shaped bracket or saddle 15 of suitable metal. The generally U-shaped saddle 15 includes a relatively long back leg 16

2

which terminates in a right angularly bent, horizontal free end portion or flange 17 which is apertured to accommodate the stud 9. Threadedly mounted on the stud 9 is a plate-like nut 18 beneath which the flange 17 of the saddle 15 is engaged. A nut 19 is threaded on the stud 9 beneath the flange 17. The nuts 18 and 19 adjustably secure the flange 17 on the stud 9 in an obvious manner.

The saddle 15 is for the reception of the pipe to be hung, as indicated at 20. A longitudinally split, tubular pad or sleeve 21 is provided on the portion of the pipe 20 which rests in the saddle 15. A clamp 22 secures the pipe 20 in the saddle 15.

The clamp 22 comprises a flat metallic band or strap 23 which is threaded through a transverse slot 24 provided therefor in the upper portion of the back leg 16 of the saddle 15. One end portion of the strap 23 passes beneath the saddle 15 and the other end portion of said strap passes over the pipe 20. The end portions of the strap 23 are adjustably and detachably connected through the medium of a metallic connector or clip 25. The clip or connector 25 includes, in the embodiment shown, a rectangular metallic plate 26 having formed integrally with one end portion thereof a transverse loop 27. Formed integrally with the other end portion of the plate 26, on the longitudinal sides thereof, are bendable ears 28. One end portion of the strap 23 is inserted through the loop 27 and is downwardly and reversely bent in a manner to provide a hook or the like 29 in which the plate 26 is engaged. The other end portion of the strap 23 is inserted between the outstanding ears 28 over the other end portion of said strap, inserted through the loop 27 and outwardly and reversely bent in a manner to provide a hook 30 in which the loop 27 is engaged and which extends between the ears 28. The ears 28 are then clinched on the reversely bent end portion or hook 30 and the connection is complete.

It is thought that the use of the hanger will be readily apparent from a consideration of the foregoing. Of course, to install the device the threaded suspension rod, shank or stud 9 is mounted on the deck structure or other overhead support beneath which the pipe is to be mounted. The saddle 15 is then slipped on the stud 9, adjusted to the desired position and secured between the threaded elements 18 and 19. It will be noted that the construction is such as to permit rotary as well as vertical adjustment. With the protective pad or sleeve 21 thereon, the pipe 20 is then engaged in the saddle 15 and firmly secured through the medium of the clamp 22. It also will be noted that the construction is such as to accommodate various sizes of pipe. An opening 31 in the flange 17 receives the stud 9. The embodiment hereinbefore described is primarily for use with light or small pipe.

The embodiment of FIGURES 5, 6 and 7 of the drawing is for relatively heavy or large pipe and, toward this end, comprises a pair of spaced threaded shanks, rods or studs 32 which are suspended from the insulated deck structure or other overhead support 12. Adjustably and removably mounted between the lower end portions of the studs 32 is a substantially inverted U-shaped saddle 33 of suitable metal. The saddle 33 is provided on its ends with integral, outwardly projecting horizontal ears or flanges 34 through which the lower end portions of the studs 32 pass. The portions 34 of the saddle 33 are secured in adjusted position on the studs 32 between pairs of nuts 35 threaded on said studs.

The saddle 33 is for the reception of the pipe to be hung, as indicated at 36. The portion of the pipe 36 which is engaged in the saddle 33 is provided with a protective sleeve or pad 37 of suitable material. The end portions of the saddle 33 are provided, adjacent the longitudinal edges of said saddle, with longitudinally elong-

3
gated openings or slots 38. The openings or slots 38 are for the passage of the straps 23 of a pair of the clamps 22 which secure the pipe 36 in the saddle 33. This is shown to advantage in FIGURE 7 of the drawing. It will be observed that the straps are threaded in opposite directions through the openings 38 while the clips or connectors 25 are located beneath opposite side portions of the pipe.

In use, the studs 32 are suspended from the deck structure 12 and the saddle 33 is mounted between said studs. The pipe 36 is then engaged beneath the saddle 33 and the clamps 22 are applied. The saddle 33 is adjustable vertically on the studs 32 by reason of the nuts 35. This vertical adjustment may be made either before or after the pipe is secured in the saddle. This also applies to the embodiment of FIGURE 1 of the drawing.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A pipe hanger assembly including a bracket member adapted to be secured to a supporting surface and including a portion adapted to support a pipe section, a strap retaining member encircling said portion and adapted to encircle said pipe section, one end portion of said strap including an inturned reversely bent terminal end portion underlying the adjacent portion of said one end portion and the other end portion of said strap being end lapped over said adjacent portion, a connector comprising a flat elongated plate having a generally rectangular transverse loop formed on one end with said plate defining one long side of said loop, a pair of outwardly projecting bendable ears carried by the other end of said plate and projecting outwardly from the longitudinal sides thereof, said strap being passed through said loop with said plate sandwiched between said terminal and adjacent portions of said strap and said other end of said plate seated in the bent portion of said strap connecting said terminal and adjacent portions of said one

end portion of said strap, said other end portion of said strap being passed through said loop and terminating in an outturned reversely bent terminal end portion passing over said loop and between said ears, said ears having their free end portions bent toward each other and over the last mentioned terminal end portion in end to end opposing relation and clamping the last mentioned terminal portion between said ears and said adjacent portion.

5 2. The combination of claim 1 wherein said bracket member comprises a channel-shaped saddle member adapted to lengthwise cradle a section of pipe, said strap also encircling said saddle member.

10 3. The combination of claim 2 wherein said saddle member includes a pair of spaced legs between whose one pair of corresponding ends a pipe section is receivable, at least one of said corresponding ends including an angulated portion adapted to be fastened to a supporting structure, said one of said corresponding ends having a slot formed therein through which said strap passes.

15 4. The combination of claim 3 including a longitudinally split sleeve having an inside diameter adapted to snugly encircle said pipe section and an outside diameter sufficient for said sleeve, when seated in said saddle member, to project outwardly beyond said one pair of corresponding ends for engagement by said strap.

20 5. The combination of claim 1 wherein said bracket member comprises a channel-shaped saddle member adapted to lengthwise cradle a section of pipe, said strap also encircling said saddle member, said saddle member including a pair of spaced legs between whose one pair of corresponding ends of the pipe section is receivable, each of said corresponding ends including an angulated portion adapted to be fastened to a supporting structure, each of said corresponding ends having a slot formed therein through which said strap passes.
